STRANDING MACHINE

Carl O. Bruestle, Metuchen, N. J., assignor to
 Syncro Machine Company, Perth Amboy, N. J.,
 a corporation of New Jersey

Application June 25, 1949, Serial No. 101,446

5 Claims. (Cl. 57—59)

1

The present invention relates to stranding machines and particularly to stranding machines of the type which is known as tube and disc. The tube and disc type stranding machine is essentially a modification of the well known tubular strander but can more readily be constructed in large sizes since a tube of sufficient size for very large wire spools requires an extremely large and costly lathe. In general, however, such tube and disc stranders have comprised a plurality of discs joined by tubes spaced about the peripheries of the discs, there being ordinarily three such tubes.

I have found that a tube and disc strander can be made to withstand much greater loads and to operate at considerably higher speeds by utilizing a plurality of tubes or rods at each of a number of spaced points about the periphery of the discs. My present invention, therefore, utilizes a tube, or rod, and disc construction for a stranding machine in which the axially spaced discs are joined by groups of tubes at spaced points about the peripheries of the discs.

It is an object of the invention to provide a stranding machine of the tube and disc type having the capabilities of operating at much higher speeds than has been true of such stranding machines in the past.

It is another object of the invention to provide for such a high speed tube and disc stranding machine by utilizing a group of tubes at each of a plurality of spaced points about the peripheries of the discs to provide the driving force from the first or driven disc through the stranding machine.

It is a further object of the invention to provide a tube and disc stranding machine so organized that in the event of failure of one of the drive tubes the damaged tube may be readily removed and a replacement therefor inserted.

Other objects and features of the invention will become apparent when the following description is taken in connection with the annexed drawings in which—

Figure 1 is a top plan view of a stranding machine in accordance with my invention;

Figure 2 is a fragmentary cross-sectional view taken on the line 2—2 of Figure 3 showing the mode of mounting a group of driving tubes in the periphery of one of the discs;

Figure 3 is a transverse sectional view of one section of a stranding machine showing details of the tube and disc structure;

Figure 4 is a fragmentary cross-sectional view of the device of Figure 3 showing particularly

the mode of mounting a reel supporting cradle on the stranding machine disc; and

Figure 5 is a transverse cross-sectional view taken on the line 5—5 of Figure 4 showing the arrangement of the driving tubes and particularly the mode of grouping the tubes at spaced points about the periphery of the discs.

Referring now to the drawings, there is shown at 10 a disc preferably of steel and provided with a rim 11 at its outer edge which rim rides upon suitable rollers which serve to support the rotating parts of the machine. Fastened to each side of each disc 10 (with the exception, of course, of the end discs) is an aluminum or other light metal casting 12 or 13 in the form of a spoked wheel having a solid periphery. The castings 12 and 13 differ slightly in that casting 12 is constructed to accommodate a member 14 which serves to support one end of a cradle 15 and likewise to provide a guide means for a wire indicated at 16 which is fed from the reel 17 mounted in the cradle 15. The other casting 13 is slightly differently constructed since it is provided with a different type of wire guide and is, therefore, not hollow as is the member 14. However, casting 13 is also provided with a supporting means for the opposite end of the reel cradle 15, as is clearly shown in the drawings and as is common in machines of this general type.

Castings 12 and 13 are each provided with openings at spaced points about their peripheries, these openings being shown in Figures 3, 4 and 5 particularly and being designated 18. In the particular instance these openings are provided in three groups spaced 120° apart and each group comprises four openings, as is clearly indicated in Figure 5. Extending between each casting 13 and its cooperating casting 12 and located in corresponding holes 18 are the tubes 20, which tubes are inserted in the openings 18 and held in position in any suitable manner as, for example, by means of the taper pins 21.

As is customary in machines of this type, the wires from the various reels are led through centrally located guides and thence to the outer portion of the disc by means of guides such as 22 and are then led through additional guides 23 and then, in the particular instance, through holes in the steel plates or discs 10 and the castings 11 and 12 and ultimately to the terminal portion 50 of the machine where they are twisted together to form the end product of the machine.

By utilization of the construction above described, the weight of the strander is materially reduced since instead of utilizing a solid tube of

large diameter there have been substituted the discs comprising the members 10, 12 and 13 and the tubes 26. This reduction in weight is a material advantage since the centrifugal forces produced by the rotation of the heavy mass of the large tube frequently used is extremely great and limits the speed of operation of the machine.

Additionally, the utilization of groups of tubes such as have been described is a material advantage as compared with the use of a single tube at each one of the spaced points about the periphery of the various discs. If a single tube were used, it would be necessary that that tube be heavier and of greater diameter in order to secure the same strength and to transmit the proper driving force. The increase in diameter of the tube would necessarily increase the radius about which the tube rotated and thus would materially increase the centrifugal force and consequent bending movements applied to the tube. By using a group of tubes, it is possible to utilize much smaller tubes and of lighter weight and, most important of all, to locate these tubes at a lesser radius from the center of rotation to thereby materially reduce the centrifugal forces exerted upon the tubes.

Great advantage is derived from this construction since the tubes, while uniform in outside diameter, may be varied in wall thickness and thus the tubes nearer the driving end of the machine be stronger than those nearer the final end so that each tube is of proper strength for transmitting the driving torque required at the particular stage where that tube is used. If desirable, of course, this variation in wall thickness may be carried to the extent where some of the tubes become solid rods.

The construction described is also of major advantage in the minimization of time required to replace a tube in the event of failure. Thus, it is only necessary in order to replace a tube to remove the discs 12 and 13 at opposite ends of a cradle 15 from their corresponding discs 10, to then remove the taper pins 21 at the ends of the tubes of that section, separate the section, remove the damaged tube and replace it, and then reverse the process to re-insert the section in the machine.

While I have described a preferred embodiment of my invention, it will be understood that modifications thereof may be utilized within the scope and spirit of my invention. Consequently, I wish to be limited not by the foregoing description but, on the contrary, solely by the claims granted to me.

What is claimed is:

1. In a stranding machine of the tubular type, in combination, a plurality of discs spaced along an axis and externally supported for rotation about that axis, a reel supporting cradle mounted between each adjacent pair of discs, said cradles being mounted upon secondary discs fixed to said first mentioned discs and a plurality of groups of tubes extending between adjacent ones of said secondary discs and fixed thereto.

2. In a stranding machine of the tubular type, in combination, a plurality of discs spaced along an axis for rotation thereabout, each said disc being flanged, means cooperating with said disc flanges for supporting them for rotation about their common axis, cradles for supporting reels of wire, means fastened to each side of each disc except the end discs for supporting one of said cradles, said means comprising plates fastened

to said discs, and means connecting adjacent ones of said plates for spacing the said plates and discs along the axis of the machine and for transmitting the driving force from the first disc to subsequent discs, said means comprising a plurality of groups of small tubes fixed in spaced bores in said plates, said groups being spaced about the peripheries of said plates.

3. In a stranding machine of the tubular type, in combination, a plurality of discs spaced along an axis for rotation thereabout, each said disc being flanged, means cooperating with said disc flanges for supporting them for rotation about their common axis, cradles for supporting reels of wire, means fastened to each side of each disc except the end discs for supporting one of said cradles, said means comprising plates fastened to said discs, and means connecting adjacent ones of said plates for spacing the said plates and discs along the axis of the machine and for transmitting the driving force from the first disc to subsequent discs, said means comprising three groups of small tubes fixed in spaced bores in said plates, said groups being spaced evenly about the peripheries of said plates.

4. In a stranding machine of the tubular type, in combination, a plurality of discs spaced along an axis for rotation thereabout, each said disc being flanged, means cooperating with said disc flanges for supporting them for rotation about their common axis, cradles for supporting reels of wire, means fastened to each side of each disc except the end discs for supporting one of said cradles, said means comprising plates fastened to said discs, and means connecting adjacent ones of said plates for spacing the said plates and discs along the axis of the machine and for transmitting the driving force from the first disc to subsequent discs, said means comprising three groups of small tubes, four tubes in each group, fixed in spaced bores in said plates, said groups being spaced evenly about the peripheries of said plates.

5. In a stranding machine of the tubular type, in combination, a plurality of discs spaced along an axis for rotation thereabout, each said disc being flanged, means cooperating with said disc flanges for supporting them for rotation about their common axis, cradles for supporting reels of wire, means fastened to each side of each disc except the end discs for supporting one of said cradles, said means comprising plates fastened to said discs, and means connecting adjacent ones of said plates for spacing the said plates and discs along the axis of the machine and for transmitting the driving force from the first disc to subsequent discs, said means comprising a plurality of groups of small tubes fixed in spaced bores in said plates, said groups being spaced about the peripheries of said plates, whereby the bending moments on the connecting tubes is reduced due to the minimum distance from the axis of rotation at which said tubes of said plurality of said groups of tubes are mounted.
